CLAIM

The ornamental design for a label printer, as shown and described.

DESCRIPTION

FIG. 1 is a front perspective view of a label printer showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2;

FIG. 13 is a partial enlarged view of FIG. 2;

FIG. 14 is a partial enlarged view of FIG. 2;

FIG. 15 is a partial enlarged view of FIG. 4;

FIG. 16 is a partial enlarged view of FIG. 4;

FIG. 17 is a partial enlarged view of FIG. 7; and,

FIG. 18 is a partial enlarged view of FIG. 8.

The dot-dot broken lines shown in the drawings depict portions of the label printer that form no part of the claimed design. The dot-dash-dot broken lines represent the bounds of the enlarged views in the figures and form no part of the claimed design.

1 Claim, 13 Drawing Sheets
